UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed December 22, 1922, Serial No. 608,558. Renewed January 24, 1927.

My invention relates to mining machines.

It has for its object to provide improved and simplified means whereby a flexibly fed mining machine utilizing a continuous flexible feeding member and having a reverse feed may be controlled during a sumping movement along its receding portion in such manner as to enable it to occupy a more varied range of initial sumping positions. A further object of my invention is to provide improved and simplified means whereby the machine may be controlled as stated, which means are applicable to standard machines without change therein. These and other objects and advantages of my invention will be hereinafter more fully described.

In the accompanying drawings I have shown for purposes of illustration one embodiment which my invention may assume in practice.

In these drawings,—

Fig. 1 is a diagrammatic view showing a standard type mining machine equipped with my improvement and operating on a face.

Fig. 2 is a detail view of the locking means.

In this illustrative construction I have shown a mining machine 1 which may be of any standard room and pillar type slidable on the mine bottom and having a cutter bar 2 projecting therefrom and a cutter chain 3 movable about the bar, together with flexible feeding mechanism including a continuous flexible feeding member 4, herein in the form of a chain, cooperating with suitable guiding means 5, 6, 7, and 8 and a feed operating member 9, the feed operating member being capable of being rotated in opposite directions at a cutting speed and in a manner described and claimed in my copending application Ren. Ser. No. 552,595, filed Mar. 30, 1918.

In my improvement, it will be observed that in spite of the fact that a continuous flexible feed member is used, the tendency of the feed operating member when drawing in its receding portion during sumping, to feed out the advancing portion and thereby insert slack in that portion, is overcome by providing means whereby the advancing portion

may be maintained of predetermined length in such manner as to insure the desired control of the angular position of the machine irrespective of the particular initial position in which the machine is placed. While these means may assume various forms they are shown herein in the form of a locking member or U clip 10 adapted to be slipped over the feed chain at a point in rear of the front guide 5 and to abut against that guide in such manner as to prevent the insertion of slack between the member 5 and the left hand rib during the sumping operation and limit the length of the advancing portion to any desired length.

Referring to the operation of my improved construction, it will be observed that when the feed operating member 9 is rotated in one direction to draw in its receding portion connected to a jack at the right hand rib, the slack inserted in the continuous flexible feeding member 4 is caused to be inserted in that member at a point between the feed operating member 9 and the guide 5 while the advance portion of the flexible feeding member is retained of the same length in such manner that, as the receding portion is drawn in, the machine is caused to swing after the connection of the member 4 to its jack at the left hand rib and thus enable the movement of the machine to be governed with such nicety as may be desired irrespective of its angle or position when sumping begins, thus facilitating and expediting the sumping operation. As soon as the sumping cut is made, the member 10 is removed, the machine then cutting across the face as usual.

As a result of my improvement, it will be noted that the range of use of a machine utilizing a continuous flexible feeding member is increased and that the operation of the same is accordingly expedited. It will also be evident that when the machine, as is usual in such machines, is adapted to cutting in the opposite direction, i. e. from left to right, with its receding portion then its advancing portion and its advancing portion its receding portion, the member 10 may then be inserted adjacent the opposite guide 5 and

function similarly. It will also be noted that if it is desired to angle the machine by drawing in its receding portion, when cutting in either direction, the member 10 may be inserted at any time. Attention is also directed to the fact that my improvement may be applied to a standard machine at small expense.

While I have in this application specifically described one form which my invention may assume in practice, it will be understood that this embodiment is shown for purposes of illustration and that the invention may be modified and embodied in various other forms and to use in connection with other flexible feed members than chains without departing from its spirit or the scope of the appended claims.

What I claim as new and desire to secure by Letters Patent is:

1. The combination with a flexibly fed mining machine having a continuous flexible feeding member presenting advancing and receding portions having free extremities, the advancing feeding portion extending laterally from the front end of the advance side of the machine and mechanism for drawing in its receding portion, of means for maintaining its advancing portion of a predetermined length during this operation.
2. The combination with a flexibly fed mining machine having a continuous flexible feeding member presenting advancing and receding portions having free extremities, the advancing feeding portion extending laterally from the front end of the advance side of the machine and mechanism for drawing in its receding portion, of means for maintaining its advancing portion of any desired predetermined length during this operation.
3. The combination with a flexibly fed mining machine having a continuous flexible feeding member presenting advancing and receding portions having free extremities, the advancing feeding portion extending laterally from the front end of the advance side of the machine and mechanism for drawing in its receding portion during stamping or angling, of means removable at will for maintaining its advancing portion of a predetermined length during either stamping or angling.
4. The combination with a mining machine having a continuous flexible feeding member and provision for disposing the same in advance and receding portions for cutting in opposite directions, the advancing feeding portion extending laterally from the front end of the advance side of the machine and means for drawing in the receding portion, of means for maintaining its advancing portion of a predetermined length during this operation irrespective of the direction of cut about to be made.
5. The combination with a flexibly fed mining machine having a continuous flexible feed

chain and provision for disposing the same in advance and receding portions for cutting in opposite directions the advancing feeding portion extending laterally from the front end of the advance side of the machine and means for drawing in the receding portion, of a removable feed chain engaging member for maintaining the advancing portion at a predetermined length during either stamping or angling and irrespective of the direction of cut about to be made.

6. The combination with a flexibly fed mining machine having a continuous flexible feeding member presenting advancing and receding portions having free extremities and guiding means for said portions including a guide member for the advancing feeding portion located at the front end of the advance side of the machine, of mechanism for drawing in its receding portion, and means adjacent said front guide member for the advancing portion for maintaining the latter of a predetermined length during this operation.

7. The combination with a flexibly fed mining machine having a continuous flexible feeding member presenting advancing and receding portions having free extremities and guiding means for said portions including a guide member for the advancing feeding portion located at the front end of the advance side of the machine, of mechanism for drawing in its receding portion, and means including a locking member carried on said advancing portion and engageable with said guide member for limiting the length of said advancing portion during this operation.

8. In a mining apparatus, a machine frame provided with cutting means, and feeding means therefor including a continuous flexible feeding member adapted to cooperate through flexible portions with stationary abutment means at opposite sides of said machine frame, which portions during transverse cutting constitute advance and receding portions, the advance feeding portion extending laterally from the front end of the advance side of the machine, a rotatable feed operating member mounted on said machine frame and engaging said flexible feeding member and adapted to traverse the latter during feeding of said frame, and means for maintaining the length of the advancing one of said flexible portions measured between its cooperating stationary abutment and said frame constant while the length of the other of said portions between its cooperating abutment and said feed operating member is diminished by the operation of said feed operating member.

9. The combination with a flexibly fed mining machine having a feed operating member and a flexible feeding element cooperating therewith, said flexible element extending laterally from the front end of the advance side of the machine and anchored at its free end at a point in advance of the machine dur-

ing feeding, of means engageable with said advance laterally extending portion of said flexible feeding element for maintaining a portion thereof between the anchor and the machine of a predetermined length while said flexible element is paid out by said feed operating member.

10. The combination with a flexibly fed mining machine having a single feed operating member and a single continuous flexible feeding element cooperating therewith having advance and receding portions anchored at their free ends at points in advance and in the rear of the machine, said advance feeding portion extending laterally from the front end of the advance side of the machine, of means for maintaining the advance feeding portion of a predetermined length while said feed operating member draws in said receding portion.

11. The combination with a flexibly fed mining machine having a feed operating member and a flexible feeding element cooperating therewith, said flexible element including a portion extending laterally from the front end of the advance side of the machine and anchored at its free end at a point in advance of the machine during feeding, of detachable means engageable with said advance laterally extending portion of said flexible feeding element and abutting against an element of the machine for maintaining said advance portion of said flexible element between the anchor and the front end of the machine of a predetermined length while said flexible element is paid out by said feed operating member.

12. The combination with a flexibly fed mining machine having a continuous flexible feeding member presenting advance and receding portions extending in opposite directions from opposite ends of the machine and having free extremities, and guiding means for said portions including a rotatable guide member for said advance portion disposed at the front end of the advance side of the machine, and mechanism for drawing in its receding portion, of detachable means engageable with said advancing feeding portion and abutting against said front guide member for preventing the advancing portion from moving relative to said guide member to maintain the advancing portion of a predetermined length during this operation.

13. The combination with a flexibly fed mining machine having a continuous flexible feeding member presenting advancing and receding portions extending in opposite directions from opposite ends of the machine and having rotatable guiding means for said portions including a guide member for said advancing portion disposed at the front end of the advance side of the machine, of mechanism for drawing in its receding portion, and means including a detachable locking mem-

ber directly engaging said advancing portion and abutting against said guide member for preventing movement of the advancing portion relative thereto for limiting the length of said advancing portion during this operation.

In testimony whereof I affix my signature.
MORRIS P. HOLMES.
